(57) **CLAIM**

The ornamental design for a pool, as shown and described.

DESCRIPTION

FIG. 1 is a perspective view of a pool.

FIG. 2 is a front view thereof.

FIG. 3 is a rear view thereof.

FIG. 4 is a right-side view thereof.

FIG. 5 is a left-side view thereof.

FIG. 6 is a top view thereof.

FIG. 7 is a bottom view thereof.

FIG. 8 is a cross-sectional view thereof, taken along line 8-8 of FIG. 6; and,

FIG. 9 is a cross-sectional view thereof, taken along line 9-9 of FIG. 6.

The broken lines shown in the drawings depict portions of the pool that form no part of the claimed design.

1 Claim, 9 Drawing Sheets
